PROCESS FOR DEHYDRATING TAR

Edwin L. Hall, Philadelphia, and Howard R. Batchelder, Drexel Hill, Pa., assignors to The United Gas Improvement Company, a corporation of Pennsylvania

Application June 27, 1940, Serial No. 342,735

13 Claims. (Cl. 252—346)

This invention pertains to the recovery of valuable hydrocarbons from tar formed during the production of combustible gas by processes involving the pyrolytic decomposition of hydrocarbon oil, with or without the aid of catalysts.

Various processes are known for the manufacture of combustible gas such as carburetted water gas and oil gas, wherein a petroleum oil such as crude oil or a fraction thereof, for example, gas oil or residuum oil, is pyrolytically decomposed.

In such processes the gas leaving the gas-making apparatus is usually brought into contact with water such as in the wash-box, and as a result the tar which separates from the gas is usually recovered in the form of an emulsion with water. Thus the tar emulsion in extreme cases may contain as high as 95% water or even higher. In some cases the tar emulsion may be in the form of a pasty solid of very high viscosity. As a rule, the tar emulsion will contain at least 50% water and in this respect differs from tars obtained in processes for the production of coal gas or coke oven gas, or in many oil cracking processes for the production of motor fuel, for in the latter processes the tar as recovered is not in an emulsion form. Therefore, the terms "tar emulsion" or "petroleum tar emulsion" as used hereinafter and in the claims refer to emulsions of tar and water produced in the manner described; namely, during the manufacture of combustible gas by processes involving the pyrolytic decomposition of petroleum oil.

The recovered mixture of tar and water from gas-making operations involving the decomposition of petroleum oil is usually first collected in a settling tank for the separation of as much water as possible by layer formation and decantation.

In accordance with prior art practice the relatively stable tar emulsion which remains after separation of the water layer is usually treated according to some method of dehydration such as centrifuging or distillation.

Centrifugal methods of treating tar emulsions, however, separate only the tar and the water of the emulsion and do not separate lighter tar constituents from the heavier. Furthermore, the presence of free carbon in the emulsion may give rise to operating difficulties.

The separation of the tar emulsion by distillation results in fractions which comprise (1) water, (2) a distillate from the tar comprising light oil and dead oil, and (3) residual tar.

For purposes of convenience in description, 55

that portion of the distillate boiling up to approximately 200° C. (392° F.) at atmospheric pressure will be designated "light oil" and that portion of the distillate boiling above approximately 200° C. (392° F.) at atmospheric pressure will be designated "dead oil." These may be separated by distillation.

The light oil fraction contains, among other things, valuable saturated and unsaturated aromatic hydrocarbons such as benzene, toluene, xylene, styrene, methyl styrene, indene, etc.

The dead oil fraction contains naphthalene, methyl and other substituted naphthalenes, and may contain anthracene, methyl anthracene, as well as numerous other hydrocarbons for the most part as yet unidentified.

The residual tar still contains polymerizable constituents.

The residual tar has a number of uses. For example, it may be used as a road tar, or as a heavy liquid fuel. For both purposes the control of the viscosity of the residual tar is of importance because of its effect upon the ease of handling.

Due to the fact that the tar is subjected to elevated temperatures for considerable lengths of time in ordinary distillation procedures of the prior art for breaking the emulsion and for the separation of light oil and dead oil as distillate, substantial polymerization is caused to take place. Such polymerization tends to reduce the quantity of distillate on the one hand because heat polymerizable constituents which are vaporizable in monomeric form are polymerized, and to increase the viscosity of the residual tar on the other, both of which are undesirable.

These disadvantages are effectively overcome in the practice of our invention.

In accordance with our invention, tar emulsions may be dehydrated in a manner (1) such that the yield of dead oil therefrom may be increased at the expense of residual tar without encountering a corresponding increase in viscosity of the residual tar; or (2) such that for a given yield of dead oil, a residual tar of lower viscosity is obtainable than by conventional methods. Furthermore, it is possible to obtain by our process a higher dead oil yield than is possible by conventional methods because it is possible to take overhead heat polymerizable constituents in monomeric form, which constituents in the prior art are polymerized and become a part of the residual tar.

Residual tar viscosity is of importance in the art. For example, an increase in tar viscosity results in an increase in handling difficulty.

With our invention, more dead oil may be recovered for any given selected residual tar viscosity than by conventional methods for tar dehydration in use at the present time.

Further features of the invention will become apparent to those skilled in the art as the specification proceeds.

In the practice of our invention a tar emulsion is rapidly heated to an appropriate temperature and then discharged into a separation zone which may be maintained at any desired suitable pressure, such as under vacuum, under conditions such that (1) the vaporized portion may be rapidly removed, and afterwards condensed and cooled to below polymerizing temperatures; and (2) the unvaporized portion may be rapidly removed and afterwards cooled to below polymerizing temperatures.

By such procedure the material in process does not remain at operating temperatures for protracted periods. Thus, polymerization is materially reduced with the result that a larger proportion of the tar itself including heat polymerizable constituents boiling in the dead oil range may be taken off overhead as distillate along with the water while processing the bottom of residual material to any given residual tar viscosity.

It will be understood that two factors affect residual tar viscosity, namely (1) the proportion of relatively fluid oils left in the residual tar which may be controlled by the proportion of volatile material removed overhead, and (2) the proportion of unsaturated material polymerized into less volatile, more viscous polymers. In our process assuming that other things remain unchanged, item 1 preceding may be increased and decreased by decrease and increase in the temperature to which the original tar is subjected. However, consideration should be given to the effect of higher temperatures upon item 2 preceding taken in conjunction with heating time. Since polymerization is a function of both temperature and time, the effect of higher temperatures during shorter heating times may be made the equivalent of the effect of lower temperatures during longer heating times. We find, however, that a relatively wide range of both temperature and heating time is afforded particularly when operating at sub-atmospheric pressures, without losing the advantage over conventional methods of tar dehydration, although we prefer to maintain item 2 preceding at a virtual minimum or at least relatively low.

Our invention may be more particularly described in connection with the accompanying drawings in which:

Figure 1 is a flow sheet illustrating one embodiment of the invention; and

Figure 2 is a flow sheet illustrating another embodiment of the invention.

Referring now to Figure 1, tar-water emulsion is introduced by pipe 2 and pump 4 into a heater 6 in which its temperature is raised appropriately and from which the heated material flows through pipe 8 into separating zone or chamber 10.

The more volatile materials contained in the tar emulsion including water, light oil and dead oil are vaporized in heater 6 and the heated mass is projected into chamber 10.

Chamber 10 is designed to facilitate the rapid separation of the vaporized and unvaporized portions. For example, it may be relatively empty.

The vaporized portion rises to the top of chamber 10, flows through line 16 to condenser 18 from

which the resulting condensate, cooled to a desired temperature, flows through line 22 to settling tank 24, and from which any uncondenser or uncondensable gas flows off such as through line 20 for further condensation, or other treatment, or otherwise, as desired.

The unvaporized portion which comprises the residual tar falls to the bottom of chamber 10, and as in the case of the vaporized portion, it is preferably rapidly removed from chamber 10 and cooled. Removal of residual tar may be accomplished either continuously or intermittently, for example, by the use of a hand operated or automatically operated valve appropriately associated with the bottom of chamber 10, or a level-operated pump, or a submerged pump in a well, each being preferably operated to avoid a considerable accumulation of tar in chamber 10.

As illustrated the residual tar is removed automatically and continuously through a liquid seal formed by the tar itself.

No particular form of apparatus is critical for this purpose, although we find that some forms are more satisfactory than others. One form which is very satisfactory is indicated diagrammatically at the bottom of chamber 10.

The base of separating chamber 10 is shown reduced in diameter thus forming well 40 which is connected to the main body of the chamber 10 by a sloping frusto-conical wall 42.

An inner pipe 44 passes through and rises from the bottom of the well 40 to create an annular zone 45. An inverted cup 46 is disposed above and around pipe 44 and as shown extends downwardly into annular zone 45.

Residual tar dropping to the bottom of chamber 10 enters annular zone 45 about the outside of cup 46, flows down around and into the inside of the cup, and overflows the top of riser 44 from which it flows through pipe 48 into residual tar cooler 50 in which the residual tar is preferably cooled sufficiently to substantially reduce or prevent any further polymerization. The residual tar flows from cooler 50 through pipe 52 to any suitable point such as to storage.

Since the liquid seal holds only a small amount of residual tar which is constantly washed away and out of chamber 10 by the newly formed residual tar, it will be seen that no portion of the residual tar after separation is held at elevated temperatures for an extended period of time.

While the flow of residual tar from chamber 10 is preferably continuous, it may be continual or intermittent if desired, for any reason. Thus, we have shown a valve 49 in pipe 48 to facilitate such continual or intermittent withdrawal, should such be desired for any reason.

Returning now to the settling tank 24, the function of which is primarily to separate the various layers which form from the condensate, it is found that an emulsion layer indicated generally at 25 sometimes forms between the hydrocarbon distillate layer indicated at 26 and the water layer indicated at 27.

Accordingly, settling tank 24 is illustrated with three outlets, 28, 29 and 30 for draining off emulsion, hydrocarbon distillate and water, respectively.

The hydrocarbon distillate may be further processed such as by fractionation to produce desired hydrocarbon fractions. For example, it might be initially separated into light oil and dead oil.

The water may be discarded or utilized in some manner, if desired.

The emulsion, if any, may be further treated to recover its hydrocarbon content. Thus, the emulsion may be passed through a filter bed capable of breaking the same, of which filter beds made of sand, lead wool, steel wool, etc., are examples. On the other hand, this emulsion might be recycled through heater 6 and chamber 10.

It is found that the ratio of emulsion (if any) to hydrocarbon distillate and water may vary considerably with operating conditions and the character of the tar undergoing treatment.

It is also found that the tendency of the hydrocarbon distillate and water to form emulsions may be very substantially reduced, if not eliminated, by fractionally condensing from the vapors leaving chamber 10 a part or all of the relatively higher boiling hydrocarbons, leaving substantially all of the water and the rest of the hydrocarbon distillate to be condensed in condenser 18 and separated in settling tank 24. This partial condensation washes from the overhead vapors any finely divided solid or semi-solid matter such as finely divided carbon particles which are apparently responsible for the formation of emulsions when they occur. Other steps may be employed for removing these particles should they occur in the vapors. Thus chamber 10 may be designed or operated in such a manner as to avoid carrying overhead emulsion-forming materials.

Any desired means may be employed for condensing out relatively high boiling hydrocarbons from the vapors flowing from separating chamber 10. For example, a partial condenser 31 is illustrated in line 16 between condenser 18 and chamber 10.

High boiling hydrocarbons condensed in condenser 31 may be drained off through outlet 32 controlled by valve 33 into cooler 34.

Other things remaining equal, the temperature to which a given tar emulsion is heated in heater 6 will depend upon the desired ratio of hydrocarbon distillate to residual tar, it being understood that the higher the temperature the higher the ratio of hydrocarbon distillate to residual tar and the higher the residual tar viscosity.

It is found that as a general rule, with other things remaining the same, including the temperature of heating, the ratio of hydrocarbon distillate to residual tar increases with increase in the percentage of water in the tar emulsion. It follows that for any given ratio of hydrocarbon distillate to residual tar the final temperature reached in heater 6 decreases with increase in percentage of water in the tar emulsion undergoing treatment.

The phenomenon is quite apparently connected with the reduction in partial pressure of the hydrocarbon distillate vapor as a result of the presence of steam generated from the water in the tar emulsion.

Accordingly, should it be desired to further decrease the partial pressure of the vapors of the hydrocarbon distillate in any case and thus, for example, take a larger proportion of hydrocarbon distillate off overhead, or the same proportion at a lower temperature, steam might be added at an appropriate point such as at 35 at the bottom of chamber 10 or at 36 at the inlet to heater 6, or at 37 at the outlet of heater 6, or at any other appropriate point or points.

It will, of course, be understood that water itself might be added at 36 since it would be vaporized to steam in passing through heater 6.

The partial pressure of hydrocarbon distillate vapors may also be reduced by reducing the pres-

sure in chamber 10, as already referred to above. This may be conveniently accomplished by attaching pressure regulating mechanism, for example, a vacuum pump, to outlet 20 of condenser 18, proper steps being taken to effectively drain condensate into settling tank 24, for instance, by inserting a vacuum leg in line 22 or connecting settling tank 24 to vacuum.

Since polymerization is a function not only of temperature but also of time, we prefer to bring the tar emulsion undergoing treatment to the desired temperature in heater 6 as rapidly as practicable and then immediately discharge it into chamber 10 for separation of its components.

15 It is also preferred to have at least the pre-ponderant part of the vaporization take place in heater 6 so as to abstract at least the preponderant part of the necessary heat of vaporization directly from heater 6. In other words, it is preferred to operate such that flashing of liquid to vapor in the separating chamber 10 occurs, if at all, only to a relatively minor extent, or at most is only incidental to the preponderant vaporization in heater 6.

25 Since for any given temperature in heater 6, other things remaining unchanged, the amount of vaporization will decrease with increase in pressure, it is preferred to choose or design heater 6 so as to have a relatively small pressure drop

30 so as to have a relatively small pressure drop between the point at which the materials undergoing treatment reach the maximum temperature and the point at which they are projected into the chamber 10. This is to permit the preponderant part of the vaporization to take place within the beater itself. This is to be done

3. within the heater itself. The total pressure drop across the heater will depend upon its design and operation and keeping in mind what has just been said, it may have any desired or convenient value high or low.

40 However, should it be desired for any reason, higher pressures might be employed.

If desired, extraneous heat may be added to chamber 10, for example, by adding superheated steam at 35° at a temperature above the average

15 steam at v at a temperature above the average temperature of chamber 10. Another means of adding heat to chamber 10 is by the insertion of a steam or other heating coil therein. Other means for adding heat to chamber 10, if desired, will occur to persons skilled in the art upon becoming familiar herewith.

Generally speaking, however, we usually prefer to restrict any heating of chamber 10 to compensate for unavoidable heat losses.

The following examples will serve to further illustrate the invention.

Example 1

60 A tar emulsion containing 75% water was processed in a small pilot plant corresponding in general to Figure 1 of the drawings. The separating chamber was operated under a pressure of approximately 50 mm. of mercury and the tar emulsion was heated in a manner such that the temperature of the materials leaving the heater was maintained at approximately 235° F.

64% of the tar (neglecting the water) was recovered as distillate and 36% as residue.

The viscosity of the tar residue in SSF @ 210° F. was 219.

A sample of the same tar emulsion processed by a conventional tar dehydration method involving distillation to the same residual tar viscosity yielded (neglecting the water) only 45% distillate, 75 and 55% tar residue.

Example 2

Another tar emulsion containing 68% water was processed in the same manner as in Example 1. The pressure in the separating chamber was held at approximately 50 mm. of mercury and the temperature of the materials in process at the outlet of the heater was maintained at approximately 257° F.

65% of the tar (neglecting the water) was recovered as distillate and 35% as residue.

The tar residue had a viscosity in SSF @ 210° F. of 165.

Another sample of the same tar emulsion processed conventionally to the same residual tar viscosity yielded (neglecting the water) only 42% distillate, and 58% tar residue.

Example 3

Another tar emulsion of a somewhat different character and containing 65% water was processed in the same manner as in Example 1, the pressure in the separating chamber being maintained at approximately 50 mm. of mercury. The temperature of the materials undergoing treatment at the outlet of the heater was maintained at approximately 268° F.

55% of the tar (neglecting the water) was recovered as distillate and 45% as residue.

The viscosity of the tar residue in SSF @ 210° F. was 530.

Another sample of the same tar emulsion processed conventionally to the same tar viscosity yielded (neglecting the water) only 39% distillate, and 61% tar residue.

The foregoing examples amply demonstrate the advantages of our process over the conventional processes of the prior art.

A separation of the hydrocarbon distillate obtained in our process into light oil and dead oil fractions shows that the large increase in hydrocarbon distillate by the practice of our process is for the major part, if not preponderantly, in dead oil.

In other words, the outstanding advantages of our process reside in the recovery of much larger percentages of dead oil than have heretofore been possible, and without disadvantageously affecting the recovery of light oil either quantitatively or qualitatively.

Thus, measurably larger quantities of dead oil are recovered without polymerizing significant quantities of the polymerizable unsaturates in the light oil fraction.

While the tar emulsion may be brought to any desired or convenient temperature in heater 6, consideration being given to its effect upon polymerization, it is preferred to use temperatures between approximately 200° and 350° F.

Likewise while any desired pressure may be maintained in chamber 10, it is preferred to operate at pressures below atmospheric. Thus the use of temperatures between approximately 200° and 350° F. in conjunction with pressures between approximately 20 and 200 mm. of mercury (absolute) is found particularly effective.

While the time interval during which a tar particle is subjected to polymerizing temperatures in passing through heater 6 and separating chamber 10 and until it is finally cooled, may vary considerably without sacrificing the advantages of our process, we prefer that this time interval be short, or in other words, that the transit of each tar particle be rapid through zones of sufficiently high temperature to cause polymerization.

Heater 6, chamber 10 and tar seal 40 lend themselves conveniently to designs by which the hold-up of materials in process may be maintained relatively small, thus lending themselves to a rapid transit of tar particles through that portion of the process in which they are subjected to polymerizing temperatures.

The apparatus is preferably so designed and operated that the time interval during which the average tar particle is subjected to temperatures higher than about 120° F. beginning in heater 6 and ending in condenser 18 or cooler 34 or cooler 50 does not exceed 30 minutes, with 5 to 15 minutes as a better figure.

15 When the highest temperatures do not greatly exceed 200° F., this time interval may be extended somewhat, and when they approach or exceed 350° F., it is preferably shorter.

Accordingly, condenser 18 and coolers 34 and 20 50 are preferably operated at temperatures below about 120° F. As an example, they may be operated at atmospheric temperature or somewhat above or below, using river water as a cooling medium.

25 It will be understood of course that the numerous and complex variables involved make it difficult to calculate the time interval just referred to with absolute accuracy. As exemplifying some of these variables may be mentioned the variations 30 in constituency of the tar emulsions, the extremely complex nature of the hydrocarbon components thereof, differences in the physical characteristics of the tar emulsions, the extreme sensitivity to heat of certain constituents thereof, etc.

35 However, it is possible by making certain simplifying assumptions to derive empirically an expression for the time interval of exposure of tar to elevated temperatures, which expression will serve for practicable purposes in performing the 40 process and will form a valid basis for comparing results obtained.

Thus, for example, it will be helpful to assume that (a) the composition of the tar emulsion is 50% water, 30% oil (light oil plus dead oil), and 45 20% residual tar; (b) the density of the tar emulsion is 62.5 lbs. per cu. ft.; (c) the increase in volume due to vaporization and/or change in temperature and pressure occurs uniformly throughout the heater, so that the average volume 50 through the heater is one-half the sum of the inlet and outlet volumes; (d) the average molecular weight of the volatilized hydrocarbon material is 130; (e) the density of the residual tar at operating temperature is 62.5 lbs. per cu. ft.; and (f) the operation conditions are at an average temperature of 250° F. in the heater and a pressure of 2 lbs. per sq. in. absolute (i. e., about 100 mm. of mercury) in the separating chamber.

55 From this it can be shown that the volume of 60 materials entering the heater is negligible in comparison with the volume of the materials leaving the heater. Hence, the average volume of materials through the heater can be taken as one-half of that leaving the heater without introducing any appreciable error.

Furthermore, for the purpose of calculating the 65 said time interval the volume of the tar distillate vapors and of the unvaporized residual tar can normally be neglected. This is because (1) the 70 volume of residual tar is relatively small in comparison to the vaporized material, and (2) the molecular weight of water is so low compared to the average molecular weights of the vaporized hydrocarbons that in the mass leaving heater 6 75 steam is present in the order of 92% or more by

volume. The calculations for the heater proper, therefore, may be made, without introducing too large an error, on the basis of the water content of the tar emulsion.

Stated generally therefore in terms of a throughput of W lbs. of water per hour, a heater temperature of $T^{\circ}R$ (Rankine), an absolute pressure in the separating chamber of P lbs. per square inch, and a heater volume of V_h cubic feet, the time of exposure in the heater in hours equals:

$$\frac{V_h}{\text{average volume of water through the heater per hour}} =$$

$$\frac{V_h P}{\frac{1}{18} W \times 359 \times \frac{T}{492} \times \frac{14.7}{P}} = \frac{V_h P}{0.3 W T}$$

If the tar well of the separating chamber has a volume in cubic feet of V_{tw} , and the yield of residual tar in pounds per hour is R_t , then the time of exposure in the tar well is represented by

$$\frac{V_{tw}}{\text{residual tar per hour (cubic feet)}} = \frac{62.5 V_{tw}}{R_t}$$

Since the time of exposure of any particular part of the hydrocarbon vapor to temperatures above $120^{\circ} F.$ after leaving heater 6 is less than that for liquid residual tar particles because of the speed with which the vapor travels to condenser 18, the approximate average total time interval (in minutes) in the entire apparatus may, therefore, conveniently be expressed as

$$60 \left(\frac{V_h P}{0.3 W T} + \frac{62.5 V_{tw}}{R_t} \right)$$

If the point in the heater at which the materials reach $120^{\circ} F.$ is determined at least approximately, and the volume of the heater substituted in the above formula is taken as from that point instead of from the inlet, the formula gives an approximation of the average time interval during which the materials in process are maintained at a temperature above $120^{\circ} F.$

As previously mentioned, the apparatus is preferably so designed and operated that the value of this expression rarely exceeds 30, with 15 as a better figure and 5 as excellent.

It will, of course, be understood that apparatus for carrying out the invention may be of any desired design, construction or shape suitable for the purpose.

Thus while chamber 10 has been shown empty, any other suitable interior structure may be adopted consistent with its function as a separating chamber.

Likewise, heater 6 may take any form or shape and may be of any type suitable for the purpose. As an example, a pipe still may be employed although a shell-and-tube heater might also be conveniently employed. The heater 6 is preferably so designed as to insure the discharge of both liquid and vapor into separating chamber 10, for example, by resorting to the self-draining principle for the liquid, or to sufficiently high vapor velocities to carry the liquid along with the vapor, or both, or otherwise. This is, of course, to avoid the separation and polymerization of tar in the heater 6 with resulting stoppages.

Likewise, condensers 18 and 31, coolers 34 and 30 and settling tank 24 may be of any desired construction suitable for their respective purposes.

While the invention has been more particularly described in connection with a single vaporization step, it is to be understood that vaporization may

be effected, if desired, in a plurality of stages, for instance, two or more.

This is more particularly illustrated in Figure 2 wherein tar emulsion is introduced by a pipe 61 and pump 62 into a heater 63 in which its temperature is raised appropriately, for example, between 190° and $230^{\circ} F.$, and from which the heated material flows through pipe 64 into separating zone or chamber 65 which may be maintained at any suitable pressure such as atmospheric.

The lighter portions of the volatile materials contained in the tar emulsion, including a substantial part of the light oil and some of the water, are vaporized in heater 63 and the heated mass is projected into chamber 65.

The vaporized portion is taken off through line 66 to condenser 67 from which the condensate flows through line 68 to settling tank 69 and from which any uncondensed or uncondensable gas flows off through line 70 for further condensation or other treatment, or otherwise, as desired.

The unvaporized portion which still contains at least a substantial part of the dead oil and the rest of the water falls to the bottom of chamber 65 and is preferably rapidly removed therefrom with a relatively small, if any, hold-up for the same reasons as given in the particular description of Figure 1 in connection with the removal of residual tar from chamber 10. Accordingly, and for convenience, chamber 65 is illustrated as having the same construction as chamber 10.

The unvaporized material flows off through pipe 71 to pump 72 and then into heater 73 in which its temperature is raised appropriately such as between $200^{\circ} F.$ and $350^{\circ} F.$, and from which the heated material flows through pipe 74 into separating zone or chamber 75 which may be maintained at any suitable pressure such as between 20 and 200 mm. of mercury, absolute.

The rest of the volatile materials which it is desired to remove from the tar and the rest of the water are vaporized in heater 73 and the heated mass is projected into chamber 75.

The vaporized portion flows off through line 76 to condenser 77 from which the condensate flows through line 78 to settling tank 79 and from which any uncondensed or uncondensable gas flows off through line 80 for further condensation or other treatment, or otherwise, as desired.

The portion left unvaporized in heater 73 and chamber 75 comprises the residual tar which falls to the bottom of chamber 75, and as in the case of the vaporized portion it is preferably rapidly removed from chamber 75 and cooled.

Accordingly, and for convenience, chamber 75 has been illustrated as of the same construction as chambers 10 and 65, although it will be understood that these chambers need not have the same construction and that any other suitable construction might be substituted.

As shown, residual tar flows off through pipe 81 into residual tar cooler 82 in which the residual tar, the same as already described in connection with Figure 1, is preferably cooled rapidly and sufficiently to substantially reduce or prevent any further polymerization. The residual tar flows from cooler 82 through pipe 83 to any suitable point, such as to storage.

The function of settling tank 69 is to separate the various layers which form from the condensate. Since an emulsion layer seldom, if ever, forms in settling tank 69 depending somewhat, of course, upon the amount of hydrocarbon distillate taken overhead, settling tank 69 is illus-

trated with two outlets 84 and 85 for draining off light hydrocarbon distillate and water respectively.

The function of settling tank 79 is also to separate the various layers which form from the condensate and since an emulsion layer might be formed, depending of course upon the design and operation of separating chamber 75, the settling tank 79 is illustrated with three outlets 86, 87 and 88 for draining off emulsion, hydrocarbon distillate and water, respectively.

It is, of course, to be understood that any tendency for an emulsion to form may be reduced or prevented the same as already described in connection with Figure 1, namely by placing a partial condenser in line 76, or by the design and/or operation of separating chamber 75, or both, or otherwise.

It is also to be understood that such emulsion, if any, may be treated to recover its hydrocarbon content the same as already described in connection with Figure 1.

The heavy hydrocarbon distillate has been illustrated in settling tank 79 for convenience as the top layer. Its density is very close to that of water and changes more rapidly with temperature. Accordingly, it is found that the heavy hydrocarbon distillate might comprise the lower layer when temperatures in settling tank 79 are somewhat low.

If desired, steam might be added to either the first or the second vaporization steps, or both, at any appropriate point or points, for example, as illustrated in Figure 1.

The same applies to the addition of supplementary heat to chambers 65 and 75.

In practice it is found that steam will be used more often in connection with the second separation step than in the first, although when the percentage of hydrocarbon distillate taken off in the first step is relatively high, some steam might be desired.

Chambers 65 and 75 may be operated at any desired pressure which may be conveniently regulated at 70 and 80 respectively, such as by venting to the atmosphere or by using pressure regulating mechanism.

Thus, chambers 65 and 75 might be operated at atmospheric, super-atmospheric or sub-atmospheric pressures, although atmospheric and sub-atmospheric pressures will usually be employed.

As an example, chamber 65 may be operated at atmospheric pressure and chamber 75 at sub-atmospheric pressure.

Thus for example, when the collection of the larger part of the light oil is in settling tank 69 and the larger part of the dead oil is in settling tank 79, chamber 65 may be operated at substantially atmospheric pressure and the temperature of the incoming materials undergoing separation may be between 190° and 230° F.; and chamber 75 may be operated at a pressure between 20 and 200 mm. of mercury and the temperature of the incoming materials may be between 200° and 350° F.

Other combinations of temperatures and pressures will suggest themselves to persons skilled in the art upon becoming familiar herewith.

As in the case of Figure 1, the time interval during which the average tar particle is subjected to temperatures higher than 120° F. preferably does not exceed 30 minutes with 15 minutes as a better figure and 5 minutes as excellent, these times being determined by the formula set forth herein. Also as in the case of Figure 1

when the highest temperatures do not greatly exceed 200° F., the time interval may be extended and when they approach or exceed the 350° F., it is preferably shorter. However, as previously stated although we prefer the time interval to be short it may vary considerably without sacrificing the advantages of our process.

A two or more stage process is particularly recommended in cases where the tar emulsion contains relatively high percentages of light materials such as benzene, since the first stage permits such materials to be condensed at a higher pressure than might be desired in the second stage, particularly if it is desired to take a considerable quantity of high boiling material off overhead in the second stage.

For example, to condense vapors having a relatively high benzene content at pressures of the order of 20 mm. of mercury might require temperatures sufficiently low to solidify benzene in the condenser after it is liquefied. Thus, taking off benzene at higher pressures such as atmospheric has distinct advantages when the benzene content of the tar emulsion is relatively high.

On the other hand, duplicate condensers might be provided and used alternately, with one thawing while the other is in use, should solidification difficulties be encountered. Other means for overcoming any such difficulties, should they occur, will become apparent to persons skilled in the art upon becoming familiar herewith.

Apparatus for a three or more stage treatment will become apparent to persons skilled in the art upon becoming familiar with the foregoing

35 Many other variations may be made.

For the purposes of the claims expressions of units of time, where occurring, are to be construed as being calculated by the empirical formula set forth herein, or its equivalent. However in the case of variations, modifications of the formula may be employed if required.

It is to be understood that the foregoing is by way of illustration and that changes, omissions, additions, substitutions and/or modifications might be made within the scope of the claims without departing from the spirit of the invention.

With respect to products produced by the process described herein reference is made to our co-pending application Serial Number 370,608, filed December 18, 1940.

We claim:

1. A process for the dehydration of a petroleum tar emulsion with the simultaneous separation of the constituents of the tar into hydrocarbon distillate and tar residue with decreased polymerization, comprising rapidly heating said tar emulsion to a temperature sufficiently high and under a pressure sufficiently low to vaporize a substantial portion of the constituents of the tar boiling above 392° F. at atmospheric pressure rapidly separating the vaporized and unvaporized portions, and then rapidly cooling the separated portions of the tar to below polymerizing temperatures.

2. A process for the dehydration of a petroleum tar emulsion with the simultaneous separation of the constituents of the tar into hydrocarbon distillate and tar residue with decreased polymerization, comprising rapidly heating said tar emulsion to a temperature sufficiently high and under a pressure sufficiently low to vaporize its more volatile constituents including a substantial portion boiling above 392° F. at atmospheric pressure, rapidly separating the resulting vapo-

rized and unvaporized portions, and rapidly cooling the separate portions of the tar to below polymerizing temperature, said process being conducted such that the average time during which tar particles are subjected to temperatures above 120° F. does not exceed 30 minutes.

3. A process for dehydrating a petroleum tar emulsion produced in the manufacture of combustible gas wherein petroleum oil is pyrolytically decomposed, said tar emulsion containing a substantial amount of water, comprising heating a rapidly moving mass of said tar emulsion under reduced pressure to a temperature between 200° and 350° F. thereby transforming a substantial portion of the hydrocarbon content of said tar emulsion boiling above 392° F. at atmospheric pressure from liquid-phase to vapor-phase within the rapidly moving mass, projecting the heated tar emulsion without large pressure drop into a separation zone maintained at a reduced pressure between 20 and 200 mm. Hg for the rapid separation of vaporized and unvaporized portions, rapidly withdrawing the vaporized portion as overhead from the separating zone, rapidly withdrawing the unvaporized portion as residual tar from the separating zone, and cooling the portions thus withdrawn to below polymerizing temperatures.

4. A process for the dehydration of a petroleum tar emulsion with the simultaneous separation of the constituents of the tar into hydrocarbon distillate and tar residue with decreased polymerization, comprising rapidly and successively heating said tar emulsion sufficiently with intermediate separation of vapors to vaporize more volatile constituents including a substantial portion boiling above 392° F. at atmospheric pressure, making a final separation of vaporized and unvaporized portions, and rapidly cooling said separated vaporized and unvaporized portions to below polymerizing temperatures.

5. A multi-stage process for dehydrating a petroleum tar emulsion produced in the manufacture of combustible gas by the pyrolytic decomposition of petroleum oil which comprises rapidly heating said tar emulsion in a continuous stream to a temperature between 190° and 230° F., said temperature being sufficiently high to vaporize a large part of said tar emulsion boiling below 392° F. at atmospheric pressure, projecting the heated tar emulsion without large pressure drop into a separation zone maintained at substantially atmospheric pressure for the rapid separation of vaporized and unvaporized portions, rapidly removing said vaporized and unvaporized portions from said separation zone, rapidly cooling the vaporized portion to below polymerizing temperatures, immediately heating the removed unvaporized portion in a continuous stream to a temperature between 200° and 350° F., said temperature being sufficiently high to vaporize a substantial portion of the remaining volatile hydrocarbon content of said tar boiling above 392° F. at atmospheric pressure, projecting said last mentioned heated portion without large pressure drop into a separation zone maintained at a pressure between 20 and 200 mm. Hg for the rapid separation of vaporized and unvaporized portions rapidly removing said last mentioned vaporized and unvaporized portions from said last mentioned separation zone, and cooling said last mentioned portions to below polymerizing temperatures.

6. In a process for the dehydration of a petro-

leum tar-water emulsion with the separation of the constituents of the tar into hydrocarbon distillate and tar residue, said tar containing heat polymerizable constituents boiling above 392° F. 5 when at atmospheric pressure, the steps of rapidly vaporizing water and tar constituents contained in a rapidly flowing stream of said petroleum tar-water emulsion, and separating the resulting vaporized and unvaporized portions, said 10 vaporization being conducted at a temperature sufficiently high to vaporize a considerable portion of the constituents of said tar which boil above 392° F. when at atmospheric pressure, and said vaporization and separation being conducted 15 sufficiently rapidly to separate in heat polymerizable form and as a part of said vaporized portion a considerable portion of said heat polymerizable constituents boiling above 392° F. when at atmospheric pressure.

7. In a process for the dehydration of a petroleum tar-water emulsion with the separation of the constituents of the tar into hydrocarbon distillate and tar residue with decreased polymerization of heat sensitive constituents of the tar which boil above 392° F. at atmospheric pressure, the steps of heating a rapidly moving stream of petroleum tar-water emulsion to a temperature sufficiently high to vaporize a considerable portion of the constituents of the tar which boil above 392° F. when at atmospheric pressure, projecting said heated stream into a separating zone and therein rapidly separating the resulting vaporized portion including water, light oil and dead oil constituents from the unvaporized portion including tar residue, said vaporization and separation being effected with sufficient rapidity to recover from the tar in heat polymerizable form a considerable portion of said heat sensitive constituents boiling above 392° F. when at atmospheric pressure as a part of said separated vaporized portion.

8. In a process for the dehydration of a petroleum tar-water emulsion with the separation of the constituents of the tar into hydrocarbon distillate and tar residue with decreased polymerization of heat sensitive constituents of the tar which boil above 392° F. when at atmospheric pressure, the steps of rapidly flowing a stream of petroleum tar-water emulsion through a heating zone and heating said stream therein to a temperature sufficiently high to vaporize a considerable portion of the constituents of said emulsion which boil below 392° F. when at atmospheric pressure, releasing the heated stream in a separating zone and therein rapidly separating the resulting vaporized constituents, rapidly flowing a stream of said separated unvaporized constituents through a second heating zone for heating therein to a temperature sufficiently high to vaporize a considerable portion of the previously unvaporized constituents boiling above 392° F. when at atmospheric pressure, releasing the heated stream resulting from said second heating step in a second separating zone and therein separating the resulting vaporized constituents from unvaporized constituents, said vaporization and separation steps being conducted sufficiently rapidly to recover from the tar as separated vaporized heat polymerizable constituents a considerable portion of the heat sensitive constituents of the tar which boil above 392° F. when at atmospheric pressure.

9. In a process for the dehydration of a petroleum tar-water emulsion with the separation of the constituents of the tar into hydrocarbon distillate and tar residue with decreased polymeriza-

tion of heat sensitive constituents of the tar which boil above 392° F. when at atmospheric pressure, the steps of rapidly flowing a stream of petroleum tar-water emulsion through a heating zone and heating said stream therein to a temperature sufficiently high under the pressure conditions obtaining to vaporize a considerable portion of the constituents of said emulsion which boil below 392° F. when at atmospheric pressure, discharging the heated stream into a separating zone maintained at substantially atmospheric pressure and therein rapidly separating the resulting vaporized constituents from unvaporized constituents, rapidly flowing a stream of said separated unvaporized constituents through a second heating zone and heating said stream therein to a temperature sufficiently high under the pressure conditions obtaining to vaporize a considerable portion of the previously unvaporized constituents boiling above 392° F. when at atmospheric pressure, discharging the heated stream resulting from said second heating step into a second separating zone maintained at a reduced pressure between approximately 20 mm. and 200 mm. of mercury and therein separating the resulting vaporized constituents from unvaporized constituents, said vaporization and separation steps being conducted sufficiently rapidly to recover from the tar as separated vaporized heat polymerizable constituents a considerable portion of the heat sensitive constituents of the tar which boil above 392° F. when at atmospheric pressure.

10. In a process for the dehydration of a petroleum tar-water emulsion with the separation of the constituents of the tar into hydrocarbon distillate and tar residue with decreased polymerization of heat sensitive constituents of the tar which boil above 392° F. when at atmospheric pressure, the steps of rapidly flowing a stream of petroleum tar-water emulsion through a heating zone and heating said stream therein under temperature conditions sufficiently high under the pressure conditions obtaining to vaporize a considerable portion of the constituents of said emulsion which boil below 392° F. when at atmospheric pressure, discharging the heated stream without large pressure drop into a separating zone maintained at approximately atmospheric pressure and therein rapidly separating the resulting vaporized constituents from unvaporized constituents, rapidly flowing a stream of said separated unvaporized constituents through a second heating zone and heating said streams therein under temperature conditions between approximately 200° and 350° F. and sufficiently high under the pressure conditions obtaining to vaporize a considerable portion of the previously unvaporized constituents boiling above 392° F. when at atmospheric pressure, discharging the heated stream resulting from said second heating step without large pressure drop into a second separating zone maintained at reduced pressure between approximately 20 mm. and 200 mm. of mercury and therein separating the resulting vaporized constituents from unvaporized constituents, said vaporizations being effected preponderantly in said heating zones as distinguished from said separating zones, and said vaporization and separation steps being conducted sufficiently rapidly to recover from the tar as separated vaporized heat polymerizable constituents a considerable portion of the heat sensitive constituents of the tar which boil above 392° F. when at atmospheric pressure.

11. In a process for the dehydration of a petroleum tar-water emulsion with the separation

of the constituents of the tar into hydrocarbon distillate and tar residue with decreased polymerization of heat sensitive constituents of the tar which boil above 392° F. when at atmospheric pressure, the steps of heating a rapidly moving stream of petroleum tar-water emulsion in a heating zone to a temperature sufficiently high under the pressure conditions obtaining to vaporize a considerable portion of the constituents of the tar which boil above 392° F. when at atmospheric pressure, discharging said heated stream without large pressure drop into a separating zone, and therein rapidly separating the resulting vaporized portion from the unvaporized portion, the preponderant part of said vaporization taking place in said heating zone as distinguished from said separating zone, and said vaporization and separation being effected with sufficient rapidity to recover from the tar in heat polymerizable form a considerable portion of said heat sensitive constituents boiling above 392° when at atmospheric pressure as a part of said separated vaporized portion.

12. In a process for the dehydration of a petroleum tar-water emulsion with the separation of the constituents of the tar into hydrocarbon distillate and tar residue with decreased polymerization of heat sensitive constituents of the tar which boil above 392° F. when at atmospheric pressure, said petroleum tar-water emulsion having been previously treated to reduce its content of material boiling below 392° F. when at atmospheric pressure, the steps of heating a rapidly moving stream of petroleum tar-water emulsion in a heating zone to a temperature between approximately 200° and 350° F. and sufficiently high under the pressure conditions obtaining to vaporize a considerable portion of the constituents of the tar which boil above 392° F. when at atmospheric pressure, discharging said heated stream without large pressure drop into a separating zone maintained at reduced pressure between approximately 20 mm. and 200 mm. of mercury and therein rapidly separating the resulting vaporized portion from the unvaporized portion, the preponderant part of said vaporization taking place in said heating zone as distinguished from said separating zone, and said vaporization and separation being effected with sufficient rapidity to recover from the tar in heat polymerizable form a considerable portion of said heat sensitive constituents boiling above 392° F. when at atmospheric pressure as a part of said separated vaporized portion.

13. In a process for the dehydration of a petroleum tar-water emulsion with the separation of the constituents of the tar into hydrocarbon distillate and tar residue with decreased polymerization of heat sensitive constituents of the tar which boil above 392° F. when at atmospheric pressure, the steps of rapidly flowing a stream of petroleum tar-water emulsion through a heating zone and heating said stream therein under temperature conditions sufficiently high under the pressure conditions obtaining to vaporize a considerable portion of the constituents of said emulsion which boil below 392° F. when at atmospheric pressure, discharging the heated stream without large pressure drop into a separating zone maintained at approximately atmospheric pressure and therein rapidly separating the resulting vaporized constituents from unvaporized constituents, rapidly flowing a stream of said separated unvaporized constituents through a second heating zone and heating said

stream therein in the presence of additional steam and under temperature conditions sufficiently high under the pressure conditions obtaining to vaporize a considerable portion of the previously unvaporized constituents boiling above 392° F. when at atmospheric pressure, discharging the heated stream resulting from said second heating step without large pressure drop into a second separating zone maintained at reduced pressure and therein separating the resulting vaporized constituents from unvaporized constituents.

10

uent, said vaporizations being effected preponderantly in said heating zones as distinguished from said separating zones, and said vaporization and separation steps being conducted sufficiently rapidly to recover from the tar as separated vaporized heat polymerizable constituents a considerable portion of the heat sensitive constituents of the tar which boil above 392° F. when at atmospheric pressure.
